WHEEL

Donald J. Reid, Pleasant Ridge, Mich., assignor to Kelsey-Hayes Company, Romulus, Mich., a corporation of Delaware

Filed Apr. 27, 1964, Ser. No. 79,709

Term of patent 14 years

(Cl. D14—30)

FIGURE 1 is an elevational view of a wheel showing my new design;

FIGURE 2 is a cross sectional view thereof taken along the line 2—2 of FIGURE 1;

FIGURE 3 is a sectional view of a spoke portion thereof taken along the line 3—3 of FIGURE 1; and

FIGURE 4 is a perspective view thereof.

I claim:

The ornamental design for a wheel, substantially as shown.
